justable delay means are connected to receive control signals from the final stage of said counter and from said clock pulse generator.

4. The apparatus of claim 3 including second inhibiting gate means, means connecting said clock pulse generator to an input of said second inhibiting gate means, means connecting the output of said shift register to a second input of said second inhibiting gate means, and means connecting an output of said second inhibiting gate means to the reset input of said flipflop whereby a clock pulse from said clock pulse generator will cause said flipflop to reset except when inhibited by an output pulse from said shift register.

ABSTRACT OF THE DISCLOSURE

A bank of multi-position switches are adjustable to set selected cores in a magnetic shift register. The set windings are connected through the cores in such patterns that when the switch wipers are moved to particular positions representing particular characters such as, for example, letters or numbers, shift pulses applied to the register will produce a serial output representing the stored information.

BACKGROUND OF THE INVENTION

The invention is in the field of code generators. In the prior art various electromechanical and electronic code generators have been used. However, most of them have been complex, expensive, cumbersome, and in many cases, delicate. This resulted in a lack of portability and ruggedness, and excessive maintenance and power consumption.

SUMMARY OF THE INVENTION

A bank of multi-position switches have their respective multiple contacts connected through different patterns of set windings to set selected cores in a magnetic core shift register so that a serial coded output peculiar to each switch position can be shifted out of the register. A switch position can represent a particular letter or other character and the serial register output can be in Morse or other code, to generate any desired output information. One obvious application is for a radio station call letter generator. Accessory gating and counting means sequence the letters and adjust the spacing between individual letters and groups of letters. The apparatus is constructed of solid state elements to lower the weight and power requirements. The results in a compact and rugged code generator which requires little maintenance or adjustment.

BRIEF DESCRIPTION OF THE DRAWINGS

FIG. 1 shows the arrangement of the principal elements of the apparatus.

FIG. 2 shows part of a magnetic shift register.

FIG. 3 shows the threading pattern of the core windings connected to one contact of a multi-position switch.

FIG. 4 is a threading diagram for all the cores required to store twenty-six call letters.

DESCRIPTION OF THE PREFERRED EMBODIMENT

The preferred embodiment of the invention is shown in FIG. 1 where three switches S1, S2, and S3, each having twenty-seven positions, are shown. In twenty-six of the switch positions, wipers W1, W2, and W3 will rest on one of twenty-six contacts C1, C2, C3, etc. Each wiper is connected to a driver 4 to receive a respective timed

2

pulse T1, T2, or T3. The like numbered contacts of each switch are connected together as shown, i.e., C1 of S1 is connected to C1 of S2 and to C1 of S3, etc. Each contact is also connected through a respective line L1-L26 to an individual setting circuit which passes through the "set" windings of selected cores of a magnetic core shift register 2. Each of the switch contacts represents a single character such as a call letter and the setting circuit to which it is connected is designed to store binary bits representing that call letter in shift register 2. Register 2 is comprised of thirteen pairs of cores connected through their respective windings as shown in FIG. 2. Each pair is comprised of an "A" or storage core 1A, 2A, etc., and a "B" or temporary storage core 1B, 2B, etc. As is well known in the art, binary "1's" and "0's" are stored in the "A" cores and when an "A" clock pulse is received on the "A" shift line, the bit stored in the "A" core will be shifted to the "B" core of that pair, and when the following "B" clock pulse is received at the "B" shift line of register 2, the bit temporarily stored in the "B" core will be shifted to the "A" core of the following pair. Thus, any bits stored in the "A" cores will move through the register, progressing through succeeding pairs of cores each time a pair of clock pulses is received at the shift inputs. When a core stores a binary "1" it is said to be "set" and when a binary "0" is stored the core is said to be "reset." The contacts C1 of S1, S2, and S3 are connected to a setting circuit shown in FIG. 3 which is connected through the set windings of the "A" cores A1, A2, A3, A5, A6, A7, A9, A10, A11, and A13. Each "A" core which is "set" stores a binary "1" which in the convention chosen may represent, in one example, a "dot" in Morse code. Binary "1's" stored in three adjacent "A" cores represent a "dash." A binary "0" represents a space and the dots and dashes are separated by a single space. A call letter is separated by three succeeding spaces, or three adjacent "0" storing "A" cores. When a pulse T1 is received from driver 4 it is forwarded over the wiper W1 through whatever contact W1 rests on, to the connected setting circuit through selected "A" cores to ground. It is apparent that when a T1 pulse traverses the setting circuit connected to contact C1 in FIG. 3, the cores set thereby will represent a stored dash, dash, dash, dot, representing the letter "J" in Morse code, when read out of shift register 2 in reverse order. Since all cores are initially in a reset condition, the cores A4, A8, and A12 will remain in a reset condition to represent the spaces between the dashes and dot. Contacts C2-C26 of switches S1-S3 are respectively connected to different setting circuits similar to that shown in FIG. 3, but threaded through different combinations of "A" cores representing, for example, different call letters. Thus, any call letter or other information desired may be stored in register 2 by moving one of wipers W1-W3 to the appropriate contact C1-C26. When the appropriate timed pulse T1, T2, or T3 is received at the wiper from driver 4, the threaded cores of the selected setting circuit are set to store the desired information. A variable rate clock 6 furnishes A and B pulses to the shift input terminals SA and SB of register 2 over lines 8 and 10. The "A" pulse passes through a normally open inhibiting gate 12 between clock 6 and register 2. Gate 12 may receive an inhibiting signal over line 14 from an adjustable one shot multi-vibrator 38 through "or" gate 16.

Assume that the wipers of W1, W2, and W3 are resting
